UNITED STATES PATENT OFFICE.

WALTER J. DUDLEY, OF BOSTON, MASSACHUSETTS.

TELEPHONE SIGNALING APPARATUS.

SPECIFICATION forming part of Letters Patent No. 278,322, dated May 29, 1883.

Application filed August 2, 1882. (No model.)

To all whom it may concern:

Be it known that I, WALTER J. DUDLEY, of Boston, county of Suffolk, State of Massachusetts, have invented an Improvement in Telephone Signaling Apparatus, of which the following description, in connection with the accompanying drawings, is a specification.

My invention relates to an individual signaling apparatus of that class in which a series of signal-controlling mechanisms in the different stations on the same circuit are synchronously moved by a mechanical motor—such, for example, as an ordinary clock-movement—each such controlling mechanism bringing the signal of each station in proper condition to be operated only at certain intervals in its uniform movement, such intervals occurring at different times in the different stations of the series, so that only one can be operated at any one moment. The said mechanisms are controlled by an electric impulse to set the signal in operation, so that by transmitting such impulses during the period at which the desired one of the said mechanisms is operative the signal thereof will be operated, all the others being unaffected, since it is not their period or interval for operation.

The present invention consists, partly, in novel mechanism for regulating the movement of all the said mechanisms, so that their periods of operation will always remain in the proper relation to one another; also, in novel mechanism for transmitting the current by which the desired one of the signals is to be set in operation; also, in the signal-controlling mechanism by which such an impulse is enabled to set one only of the series of signals in operation; also, in the combination, with the said signal-controlling mechanism, of a switch by which the telephones of the series are removed from the circuit at all the stations except the one where the communication is going on, and secrecy is thus maintained.

At the central office is located a main regulating motor or clock, connected with a battery and the circuits on which the signaling apparatus is located, and provided with circuit-controlling mechanism, by which the current of the said battery is normally kept flowing in one direction over the line, except at certain moments when the battery is short-

circuited, these moments being shown as occurring once in each rotation of the second-handarbor or once a minute. The corresponding arbors of the signaling mechanisms or clocks, which are regulated to run a trifle faster than the central-office clock, are provided with a stopping electro-magnet, the armature of which, when attracted, engages a certain portion of the clock-work, (shown as the escapement-lever,) and thus stops the clock until the said armature is released by the diversion of the battery-current from the line by the main clock, as before mentioned, when the signaling-clocks are all released in unison with one another and with the main clock. The signaling-clocks carry cams, which, during definite portions of their rotation, open a circuit-closer which at other times closes a shunt for the entire apparatus, (except in some instances the regulating-magnet just described.) The said shunt is composed partly of the armature of a polarized relay or switch, the coils of which are normally shunted, as just mentioned, but which are brought in circuit by the momentary opening of the circuit-closer, caused by the rotation of the cam, as just described. The opening of this circuit-closer merely throws the coils of the polarized switch into circuit, the remaining apparatus (telephone, signal-magnet, &c.) being shunted by the armature thereof; but if a reverse current is sent over the line while the coils of the relay are thus in circuit, the position of its armature will be changed, it then opening the shunt around the telephone and signal-magnet, and thus bringing them into circuit and retaining them so after the shunt of the said polarized relay is again closed by the further movement of the cam which momentarily opened it. The transmitting apparatus at the central office is adapted to send the reversed current at the proper moment when the desired one of the polarized relays is in circuit. The telephone-hook is adapted to close a shunt around the signal-magnet when relieved of the weight of telephone, so that the bell will cease to ring as soon as the person called takes up his telephone. The telephone-supporting lever is itself arranged to reverse the connections of the polarized relay in the main circuit, so that when the telephone is

taken off its hook the normal current employed for regulating the clocks will, when it passes through the said relay by the opening of its shunt, as before mentioned, change the position of the armature of the said relay to bring the telephone into circuit. By employing a relay or switch to bring the telephone and signal into circuit only a short interval of time has to be devoted to each station in which the 10 said switch is operated, after which the said signal remains in circuit after the interval devoted to the said apparatus for bringing its signal into operation has elapsed.

Figure 1 is a diagram illustrating the essential parts of the regulating and a portion of the transmitting apparatus at the central office; Fig. 2, a plan view of the portion of the transmitting apparatus manipulated by the operator; Fig. 3, a detail showing the construction and operation of the pole-changing key thereof; Fig. 4, a diagram illustrating the signaling apparatus and circuits at one of the stations; Fig. 5, a modification thereof; Fig. 6, a plan view of the switch-magnet shown in Fig. 5, also showing the telephone-supporting lever in its other position; and Fig. 7, a front view of the signaling apparatus at a station, the different electro-magnets and some of the circuit-wires being indicated in dotted lines.

Referring to Fig. 1, *a* represents an arbor of the main regulating-clock, preferably the one carrying the seconds-hand, which rotates once in a minute, the said arbor being in electrical contact, through the spring 2 and wire 3, with one pole of the battery B, while the other pole of the said battery is connected with a spring, 4, that rests on an insulating-drum, *a*², on the arbor *a*, the said drum having at one point a metal stud, 5, connected with the said arbor and adapted to complete the circuit of the battery B between the springs 2 and 4 once in each rotation of the arbor *a*. The pendulum-crutch *b* of the said clock is provided with a stud, *b*¹, which, at each oscillation, lifts a spring, *b*², from a contact-point, *b*³, and thus breaks the circuit of the battery B', as will be clearly understood from the drawings. The circuit of the said battery B' includes the coils of electro-magnets *c*, as many as desired, the armature-levers *c*¹ of which are provided with pawls *c*², which, in the vibration of the said armatures produced by the attraction of the said magnets *c*, interrupted, as just described, by the action of the pendulum of the main clock, will engage the teeth of the ratchet *d*, mounted on arbors *e*, producing a rotation of the said arbors in unison with the advance of the escape-wheel of the main clock. The said ratchets *d* have one or two less teeth than the number of the vibrations of the pendulum required for a full rotation of the arbor *a* of the main clock, so that they will gain usually about one-sixtieth upon the said arbor *a* in their rotation, 60 and the said ratchets are provided with a stop-projection, *d*¹, which, nearly at the end of their rotation, comes in contact with the armature-levers *d*² of electro-magnets *d*³, included in the circuit of the battery B and springs 2 4, before described. The said armature-levers *d*², when unattracted, (which is their normal condition, the circuit of the battery B being open for the greater part of the time,) will engage the stop projection *d*¹ and arrest the ratchet *d* until the stud 5, connected with the arbor *a*, 70 touches the spring 4, completing the circuit of the battery B, and magnetizes the magnets *d*³, so that their armatures are attracted away from the stop projection *d*¹, causing the said ratchets to start in unison at a point determined by the position of the stud 5 connected with the arbor *a*.

The arbors *e* carry the transmitting apparatus for the different circuits through the stations to be signaled, the apparatus of one of which is shown in Figs. 4 to 7, it containing a clock-work regulated to carry an arbor, *m*, substantially in unison with the main regulating-clock. The said arbors *m* are kept in unison with the transmitting-arbors *e* in a 90 manner analogous to that by which the movement of the arbors *e* are kept in unison with that of the arbor *a*—that is, the arbors *m* carry disks *m*², provided with projections *m*¹, adapted to control a circuit-closer, *N*, in a 95 shunt for the regulating-magnet *n*', the circuit of which is also controlled by the arbors *e* at the central station. The armature-lever *n*, when attracted by its magnet *n*', is brought against the lever *l* of the escapement of the 100 clock-work and bears it into an extreme position, locking the teeth of the scape-wheel *l*', as shown in Fig. 4, and thus stopping the train. When the armature is released by the demagnetization of the magnet *n*', caused by the arbor *e*, as hereinafter described, the balance will 105 at once oscillate and the train start, a result which might not always ensue if the balance were allowed to come to rest in an intermediate position.

It will be seen that in the station apparatus the clock-works are stopped when the armatures are attracted, and released when they are unattracted, the reverse of the operation of the projections *d*¹ *d*² *d*³, before described. 115 The circuit of these regulating-magnets *n*' is as follows: The main battery B², Fig. 2, has its opposite poles connected by wires 12 and 13 with the springs 14 15 of the pole-reversing key *f*. (See Fig. 3.) These springs are fixed at 120 one end upon but insulated from the said key, and at their other ends may rest in electrical contact with the said key, or with stops 16 17, they being so arranged that when either one of the said springs is in contact with its stop 125 the other is in contact with the key, which is connected with the ground by wire 18.

The stop 16 is connected with the line L directly by wire 19, so that in the normal position of the key (shown in Fig. 3) the line L is 130 connected with the spring 14 and by wire 12 with one pole—for example, the positive one—of the battery B², while the other pole thereof is connected by wire 13, spring 15, and key *f*

with the ground, and a positive current will then flow through the line L. By depressing the key the pole connected with the wire 12 will be connected by spring 14 and key f with the ground, while the other—that is, the negative pole—will be connected through wire 13 and spring 15 with the stop 17, which is adapted to be connected to line, as hereinafter described, to send a negative current through the line L.

A branch wire, 20, connects the wire 19 with a spring, 22, in contact with the transmitting arbor e, and a spring, 24, connected by wire 26 with the ground, rests in contact with insulating-drum e² on the arbor e, but is brought by the stud 25 once in each revolution of the said arbor into electrical contact therewith, and thus into connection with the spring 22, thereby grounding the wires 19 and 20 and positive pole of the battery B², forming a short circuit therefor and diverting the current from the line, so that the armatures of the magnets n' are retracted and release the escapement-levers l, permitting the arbors m to start in unison at a point determined by the position of the stud 25 in the insulating-drum e².

It will be understood that the magnets n' are brought into circuit by the opening of the circuit-closer N just before the current is diverted therefrom, the difference in time between these operations being merely the variation in running between the two arbors m and e.

The disk m² on the arbor m is provided with one or more cam projections, m³, which, in the rotation of the said arbor, act upon a spring or circuit-closer, o, to raise it from contact with its stop or contact-point o'.

The projections m³ of the apparatus at the different stations are differently located relative to the stop-point m', so that the springs o will be acted upon at different moments in the synchronous rotation of the said arbors m, and no two of the said springs will be raised at the same time.

The circuit of the main line L, after passing through the magnet n' or circuit-closer N, is continued by wire 31 to the stop o', and thence, when the spring o is in contact therewith, by the wire 32 to the armature p of an electromagnet, p', so arranged or polarized that when the normal current passes through its coils the said armature will be placed in contact with a stop, p², connected by wire 33 with the main line L, leading to the next station. Thus in the normal condition of the parts o o' and p p² being connected, a direct circuit will be formed from the magnet n' or circuit-closer N to the next station, and the coils of the magnet p' and other apparatus in the station will be shunted.

The magnet p' and its armature p constitute a polarized switch, which will remain in whatever position it was placed by the last attractive impulse of the magnet p'. When the spring o is raised, breaking the connection between the wires 31-32, the current will be obliged to

pass by wire 34 to the lever r, pivoted at 35, and provided with a hook to support the usual hand-telephone, T, the weight of which holds the said lever depressed in the position shown in full lines, Fig. 4. The said lever is provided with springs r' r², insulated therefrom at one end, and adapted to have their other ends in contact, one with the said key and the other with a stop, r³, connected by wire 36 with the armature p, and when the said armature is in contact with its stop p² with the line L, leading to the next station.

The springs r' r² are connected by wires 37-38, 80 respectively, with the electrodes of the magnet p', so that the movement of the lever r on its pivot, caused by removing or replacing the telephone, will reverse the connection of the said magnet in the line L in a manner precisely similar to the operation of the key f in reversing the connections of battery B² in the said line, as before described. It will thus be seen that if the telephone be on its lever (the position shown in full lines) and the spring o is raised, the normal line-current will pass through the magnet p' and will merely attract the armature p against the stop p², thus forming a direct circuit from the coils of the said magnet to the line L, leading to the next station; but if at the moment 95 when the spring o is raised the current through the magnet p' should be reversed, its armature would be attracted away from the stop p², thus disconnecting it from the wire 33 and line L, leading to the next station. In this condition 100 of affairs the current will pass from the wire 36 by the wire 40, including an ordinary break-circuit key, s, to the coils of the telephone T, and thence by wire 41, through the magnet of the signal, (shown as an ordinary vibrating 105 bell, S,) to the line L, leading to the next station.

It will be seen that the magnet p' can only be affected when the spring o is raised, and that the telephone T and signal S can only be 110 brought in circuit when the said spring is raised, and the current through the magnet p' reversed, which is accomplished when it is desired to signal a station from the central office by the transmitting mechanism shown in Figs. 115 1, 2, 3, in the following manner:

The arbor e is provided with a contact-spring, g, in electrical connection therewith, and caused by the rotary movement thereof to pass over a series of plates, g', marked with the numbers 120 1 2 3 4 5, which are duplicated, so that the spring makes two connections with a plate bearing a given number in one revolution. These plates are placed in such relative position to the stud 25, governing the regulating 125 magnets n' at the different stations, that the spring g will be passing over the plate marked 1 while the projections m³ are raising the spring o at station 1, and over the plate 2 while the said projections are raising the spring o in the 130 apparatus at station 2, and so on, so that an impulse sent while the spring g is passing over any one of the said plates will pass through and affect the magnet p' at the station bearing

the same number, and at no other station. The said plates 1 2 3 4 5 are connected by wires 51 52 53 54 55 with a series of plates, g^4 , bearing the same numbers on the key-board of the transmitting device shown in Fig. 2, which is also provided with a metallic finger or pointer, h , which can be placed by the operator in contact with any desired one of the said plates. The said pointer h is connected with the stop 17 of the pole-changing key f by wire 56, so that when the said key is depressed, connecting the positive pole of the battery B^2 with the ground, as before described, the negative pole will be connected through the wire 13, spring 15, stop 17, and wire 56 with the pointer h , and whichever one of the plates g^4 it may be resting on, and thence by one of the wires 51 to 55, with the corresponding plate g^3 near the arbor e , and consequently when the spring 20 g , in the rotation of the said arbor, touches the said plate the circuit will be continued to the said spring and arbor, and thence by spring 22 and wire 20 to the line L , thus sending a negative impulse over the line, which, as before mentioned, will affect the magnet p' of that station only which has the same number as the plate touched by the pointer h . The current thus transmitted, being of opposite polarity to the normal current sent when the key 30 f is not depressed, will move the armature p at the station in question out of contact with its stop p^2 , thus causing the current to traverse the circuit consisting of the wire 40, telephone T , wire 41, and magnet of the signal S , causing the said signal to ring in the station where the armature p has been thus moved.

A signal or tap bell, S' , (see Fig. 2,) is included in the circuit of the battery B^2 at the central office, and when the said circuit is thus closed by the spring g the said bell will sound, after which the operator, who has kept the key depressed until the spring g closed the circuit, will release the said key, permitting the normal current to again flow and operate the signal S , the shunt o' being now closed by the further movement of the arbor m so that the normal current does not restore the armature p . Thus, by placing the pointer h on that one of the plates g^4 bearing any desired number and depressing the key f the signal will be rung at the station bearing that number and at no other.

The telephone-lever r is provided with an insulated contact-point, 42, connected with the wire 41, and arranged to be brought in contact with the stop 43, connected by wire 44 with the line L , leading to the next station when the telephone is removed, and thus shunting the signal S , so that it will cease to sound as soon as the person called takes up the telephone.

In order to signal the central office from the subscriber's station the telephone at the said station must be removed from its hook, thus reversing the connection of the magnet p' in the main line, so that as soon as it is brought in circuit by the raising of the spring o in the

rotation of the disk m^2 , its armature p will be moved by the normal current passing through it in the direction opposite its usual direction, 70 this movement of the armature bringing the key s and telephone T in circuit, as before described, but the signal S being shunted by the contact of the points 42 43. The operator, by manipulating the key s , will affect the signal 75 S' at the central office.

When two subscribers on the same or different lines are placed in communication the battery B^2 will be removed from the said lines, and the armatures p at all the other stations on the 80 said lines will serve as secrecy-switches, as it is obvious that they cannot be moved to bring the telephone in circuit in the absence of the battery-current. When the communication is ended and the telephones are again hung up, 85 and the normal battery-current thrown on the line, it will, the moment the spring o is again raised, pass through the magnet p and restore its armature to the normal condition, shunting the telephone and signal. 90

In the modification shown in Figs. 5, 6 a single magnet, $p' n'$, is employed both for regulating the clock-work and operating the switch-lever or armature p . A single circuit-closer, o , is needed to shunt the magnet both for signaling and regulating the clocks, and an additional point, m^4 , is employed on the cam-disk m^2 to raise the said spring and bring the magnet in circuit at the time for arresting the clock. 100

The neutral armature upon the armature-lever n operates for regulating, and is shown in this instance as engaging the stop-point m' on the disk m^2 to stop the clock. The telephone-lever r in this instance has a single spring, r' , 105 which is connected by wire 34 with the line L entering the station, and the said lever itself is connected by wire 37 with one electrode of magnet $p' n'$, while the stop r^3 is connected by wire 38 with the other electrode of the said magnet. The said magnet is connected at a point between its two coils (see Fig. 6) by wire 60, with its armature p , which is shown as rocking on a pivot between the said poles. By this arrangement, when the telephone is on its hook, as shown in Fig. 5, and the armature p in contact with its stop p^2 , when the spring o is raised by one of the projections m^3 , the current entering will pass by wire 34, spring r' , stop r^3 , wire 38, through the coil 70 of the magnet 110 $p' n'$, and thence by wire 60, armature p , stop p^2 , and wire 33 to the line L , leading to the next station. The normal or positive current, passing in this way through the coil 70, will tend to hold the armature p against the stop p^2 ; 115 but the reverse current, if transmitted from the central office, as before described, will remove the armature from the stop, causing the circuit to be continued from wire 60 by wire 40 and key 5 through the telephone T , wire 41, 120 and signal S , as before described. When, however, the telephone is removed, as shown in Fig. 6, the current will pass from wire 34 through spring r' , lever r , and wire 37, through

125

the coil 71 of the magnet $n' p'$, and thence by wire 60, armature p , stop p^2 , and wire 33, as before, and the said coil 71 is so wound that the normal current passing through it in this manner will move the armature d away from its stop p^2 , thus bringing the key s and telephone T in circuit, as before, when the subscriber may call the central office by manipulating the said key. The wire 60 is also connected by wire 61, Fig. 5, with a stop, t , for a spring, t' , connected by wire 62 with the wire 40 and line L , leading to the next station, the said spring being controlled by a second cam, u , on the arbor m , by which it is kept raised except when the arbor is stopped in the act of regulating it, when the said spring closes the circuit from the wire 60 to line L , thus preventing interference from the key s with the operation of regulating.

A local battery, B^3 , may be employed in connection with the key f , as shown, for the purpose of signaling the central office when a communication is ended, the main battery being cut off.

A blank space, y , is preferably left between the plates g^3 , touched by the springs g of the transmitting apparatus, as shown in Fig. 1, to insure non-interference with the operation of regulating the clocks, which takes place just before the spring g passes off from the said blank space. An insulating space, y^2 , is also left for the pointer h when not in use, as shown in Fig. 2. It is obvious that the different arbors e and their operating and controlling magnets c d^3 may be omitted, the springs d and co-operating devices being mounted directly on the arbor a , which may be extended a sufficient length to accommodate any desired number of independent transmitting devices, such as shown at the arbor e .

I claim—

1. In a telephone signal apparatus, the combination, with a main-line circuit, of an electro-magnet and its armature, constituting a switch controlling a shunt for a signal-magnet, and a shunt for the said switch electro-magnet and circuit-closer therein, controlled by a uniformly-moving motor or clock-work arranged, as described, to open the said shunt only during a definite portion of its movement, whereby the said switch-magnet can be affected only at definite moments to control the shunt for the signal-magnet, substantially as described.

2. The combination of an arbor adapted to have a uniform movement with an electro-magnet and its armature to arrest the said arbor, and thereafter to release it in unison with others of a series in the same circuit, and with an electro-magnet and its armature, constituting a switch, and communicating and signaling apparatus, and a shunt therefor controlled by the said switch, and a shunt for the said switch-magnet, controlled by the said arbor, substantially as and for the purpose set forth.

3. The combination, with a telephone and an electric magnet and its armature controlling a shunt therefor, of the telephone-supporting lever, contact-springs thereon, and contact-stops therefor connected with the electrodes of the said magnet and with the line entering and leaving the station, as described, whereby the connections of the said magnet in the line are reversed by the movement of the lever caused by the removal or restoration of the weight of the telephone, substantially as and for the purpose described.

4. A clock-work having a vibrating governor and circuit-closer operated thereby, combined with a ratchet having a stopping projection, an electro-magnet in circuit with the said circuit-closer, and provided with an armature and pawl co-operating with the said ratchet, a circuit-closer operated by an arbor of the said clock-work, and an electro-magnet in circuit therewith having an armature-lever movable into and from a position to engage the said ratchet-stopping projection, the said ratchet having less teeth than the number of times the clock-governor closes the circuit controlled by it between two successive operations of the circuit-closer operated by the clock-arbor, whereby the said ratchet is caused to rotate substantially in unison with the clock-arbor, and is brought in exact unison therewith once in each complete rotation, substantially as described.

5. In an individual signal apparatus, a series of station apparatus each containing a signal-controlling arbor adapted to rotate in unison with the others, and a polarized switch controlled thereby, combined with a transmitting-arbor rotated in unison with said signal-controlling arbors, a circuit-closer carried thereby, and a pole-changing key and transmitting device under control of the operator, whereby a battery may have one of its poles connected to the line by the said circuit-closer during any desired portion of its revolution, substantially as and for the purpose described.

6. In a telephone signal apparatus, a series of synchronously-moving devices and regulating electro-magnets therefor, combined with circuit-breaking keys, shunt-circuits for said keys, and controlling devices for said shunt-circuits, operated by the said synchronously-moving devices and arranged as described, whereby the said keys are cut out of circuit while the controlling-magnets are operating to regulate the said devices, substantially as described.

In testimony whereof I have signed my name to this specification in the presence of two subscribing witnesses.
